UNITED STATES PATENT OFFICE

BERNIS M. SHIPLEY, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Original application filed January 19, 1924, Serial No. 687,305. Divided and this application filed March 29, 1927. Serial No. 179,303.

This invention relates to cash registers and the like machines, and more particularly to key locking and controlling mechanism therefor.

5 The invention is shown applied to a well known type of machine, a complete description of which is contained in applications for Letters Patent of the United States, Ser. Nos. 608,281 and 687,305, filed by B. M. Shipley 55 on December 21, 1922 and January 19, 1924, respectively. This application is a division 60 of the latter.

10 One object of this invention is to provide a locking mechanism for depressible keys, which is under the control of said keys.

Another object is to control the unlocking of the keys by a manipulative lever on certain operations.

15 With these and incidental objects in view, the invention consists of certain novel features of construction and combinations of parts, the essential elements of which are set forth in appended claims and a preferred 20 form or embodiment of which is hereinafter 25 described with reference to the drawings which accompany and form part of this specification.

Of said drawings:

20 Fig. 1 is a section through the machine to 30 the right of the transaction bank of keys.

Fig. 2 is an enlarged detail view of a part 35 of the interlocking mechanism associated with the transaction bank.

Fig. 3 is a detail view of the releasing bar 40 together with a part of the locking mechanism associated therewith.

Fig. 4 shows a part of the mechanism 45 shown in Fig. 3 in position for a single item transaction.

Fig. 5 is a detail view of the total taking 50 lever and a part of the mechanism controlled thereby.

Fig. 6 is an elevation of the right hand end 55 of the machine showing the operating mechanism and a part of the releasing mechanism.

The above cited applications disclose a 60 machine provided with a plurality of banks of amount keys with each of which is associated a differential mechanism for the purpose of adjusting indicators, type carriers

and totalizers, commensurate with the amounts set up on the amount keys. The machine is also provided with a bank of clerks' keys and a bank of transaction keys. The transaction keys, by means of the differential mechanism, control the printing mechanism and select the totalizers, a plurality of which is provided for accumulating transactions and classifications of transactions. The transaction keys also control the operation of the machine for entering single item and multiple item transactions.

Only such of the above mechanism as forms a part of the present invention is shown in the drawings which form a part of this application.

The machine to which this invention is shown applied, is well adapted for use in business places where it is desired to register a plurality of items and then issue a receipt upon which is printed the amount of each item together with the total thereof.

The keyboard of the present machine is substantially the same as that disclosed in the above cited applications and as this invention is more particularly directed to the transaction keys, a description thereof will be given forthwith.

Transaction keys

The transaction keys comprise two groups arranged in a single bank and mounted in a common frame 33 (Fig. 1) supported by rods 34 extending between the side plates of the machine. The upper group of keys 30 is used 85 in registering multiple item transactions, and the lower group of keys 31 is used in registering single item transactions.

The keys are held in their normal positions by the usual springs (not shown) and are retained in their depressed positions by a spring-actuated locking detent bar 35 engaging pins 36 on the keys.

The detent bar 35 is pivotally mounted on links 37 and 38, which swing on pins carried by the key frame 33.

The key pins 36 also wipe against the beveled walls of recesses formed on a movable releasing bar 39, to shift the bar and operate interlocking mechanism between the transac-

tion keys and a starting key bar 105, Fig. 6. The releasing bar 39 is pivotally supported by links 40 and 41 (Figs. 3 and 4) also pivoted on the key frame 33.

5 A release key 32 is located on the key frame between the groups of multiple and single item keys 30 and 31, respectively. The release key 32 is equipped with a pin 36 to shift the detent bar 35, and release an accidentally depressed transaction key in either group, as 10 illustrated in Fig. 1.

Any of the "single item" keys 31, when 15 depressed, contacts its key pin 36 against the inclined end of a usual retaining hook on the detent bar 35 to shift the bar and hook against the tension of a usual restoring spring 351 so that after the pin 36 passes below the bill of the hook, the spring 351 will return the detent bar to latch the hook over the pin 20 and retain the key 30 in depressed position. Depression of another key 30 will release the key first depressed in a well-known manner.

The pin 36 of the "single item" key 31, when the latter is depressed, will also contact 25 the beveled wall of that recess in the movable releasing bar 39 which lies in the path of the pin, to shift the releasing bar and operate interlocking mechanism (later described), the hook of the detent bar 35, by retaining the key 30 in depressed position also causes the key, 30 through its pin 36, to retain the releasing bar 39 in shifted position.

Differential mechanism

35 Associated with the transaction keys is a differential mechanism provided for the purpose of selecting totalizers, adjusting indicators (not shown) and printing mechanism (not shown). This differential mechanism 40 also co-operates with the transaction key locking mechanism, as will be hereinafter described.

To drive the differential mechanism a drive 45 shaft 42 is provided with a pair of cams 43 pinned thereto and co-operating with rollers 44, carried by a Y-shaped lever 45. This lever is pivoted on the differential hanger 46 and, at its upper end is connected to a segment 47 by means of the link 48. The shaft 42 receives a complete clockwise rotation on each 50 cycle of operation of the machine, which through the mechanism just described, rocks the segment 47 first clockwise and then counter-clockwise to its normal position. A differentially movable arm 49 carries a latch 50 supported thereon by a bell crank 51 and an arm 52. The latch 50 normally connects the arm 49 to the segment 47. As the segment 47 moves clockwise, the differentially movable 55 arm 49 is carried with it until an arm 53, of the bell crank 51, strikes the end of the depressed key, whereupon the bell crank is rocked counter-clockwise to disengage the latch 50 from the segment 47. As the latch is 60 thus disengaged, a nose 54 thereon moves into

engagement with a notch 55 in a bar 56 supported at its upper end by the hanger 46 and at its lower end by a rod 57. As the segment 47 returns to its normal position the differentially movable arm 49 is again connected thereto and is returned to its normal position.

Interlocking mechanism

When entering a multiple item transaction, the operated transaction key 30 should be locked in depressed position, and all other transaction keys locked against depression until the completion of the entire transaction.

This result may be conveniently obtained by arranging the inclined walls of those recesses in the releasing bar 39 which lie in the paths of the "multiple item" keys 30, so that upon depression of a key 30, the releasing bar 39 is given a greater extent of movement than is imparted to it by the "single item" keys 31, and by providing the link 41, to which the lower end of the releasing bar 39 is pivoted, with a notch 65 (Fig. 4) engageable by a locking bail 64 journaled on a shaft 61.

When a "single item" key 31 is depressed, the releasing bar 39 is not shifted a sufficient distance to swing the notched link 41 far enough to bring the notch 65 into the path of the locking bail 64. But, owing to the longer incline of the walls of the releasing bar 39, beneath the "multiple item" keys 30, depression of a "multiple item" key will shift the releasing bar 39 and its link 41 to such an extent, that upon complete depression of the key, and the restoring of the detent bar 35, and its link 38 to locking position, the notch 65 in the link 41 is in the path of the locking bail 64, preparatory to the entry of the edge of the locking bail 64 thereinto.

An arm 60 pivoted on the release shaft 61 is fast with the locking bail 64 to control the latter. The inner free end of the bail arm 60 extends inwardly into the path of a stud 63 projecting from the differentially movable arm 49, which stud maintains the bail arm 60 and the locking bail 64 in idle position against the tension of a spring 62 connected with the arm 60 which tends to rock the arm 60 and locking bail 64 counter-clockwise (Fig. 3) towards the link 41.

Depression of an item key, and amount keys, followed by an operation of the machine, rocks the differential arm 49 clockwise as previously described, to select the proper totalizer, and in so doing the differential arm 49 releases the bail carrying arm 60 to the action of the spring 62, which rocks the arm 60 and its locking bail 64 counter-clockwise.

The bail then enters the notch 65 to hold the depressed "multiple item" key 30 in its depressed position throughout two or more operations of the machine.

The extended travel permitted the locking bail 64 when it enters the notch 65 in the link 41, positions the bail beneath the link 38 and

thereby locks all the other keys in the item bank against depression.

When a "single item" key 31 is depressed, and the machine is operated, the limited travel permitted the locking bail 64 is such that the free end of the bail arm 60 remains in the path of the stud 63 when the bail contacts the unnotched end of the link 41, so that upon the return of the differential arm 49 at the end of the operation, the stud 63 contacts the bail arm 60 and restores it together with the bail 64, to idle position. But when a "multiple item" key 30 is depressed and the machine operated, the extended travel 15 of the bail 64 withdraws the free end of the arm 60 from the path of the stud 63 on the differential arm 49.

Therefore, to effect the release of the multiple item keys 30, and the restoring of the locking bail 64 to its idle position, a total lever 20 70 (Fig. 5) of the usual type, and having the usual cam slot 74, is provided. After all the items of a "multiple item" transaction have been entered in the machine, the total lever 25 70 is manually shifted from its normal "add" position to the "item total" position, and after the total is printed, the total lever is restored to its normal "add" position.

A roller 73 carried on one arm of a lever 30 71, pivoted at 72 enters the cam slot 74, the opposite arm 76 of the lever having formed on one edge thereof a cam recess 761. A link 75 also pivoted at 72 and overlying the arm 76 of the lever 71 has a complementary cam recess 78 formed on its edge, which cooperates with the cam recess 761 formed in the arm 76 of the lever 71 to constitute a cam slot. A spring 77 connects a stud 751 on the link 75 with the arm 76 of the lever 71 to hold these parts together with the stud 751 in contact with the upper end of the arm 76. This arrangement provides a flexible cam mechanism which will yield to prevent injury to the machine in case the shaft 61 is locked by a depressed key, at the time the total lever 70 is shifted from its "add" position. A crank 80 fast on the shaft 61, on which the bail carrying arm 64 is pivoted, carries a roller 79 entered in the cam slot 55 56 formed by the complementary cam edges 761 and 78 of the arm 76 of the lever 71 and the link 75.

When the total lever 70 is adjusted from its "add" position to its "item total" position, 55 its cam slot 74 rocks the lever 71 in counter-clockwise direction (Fig. 5) and the arm 76 thereof, together with the link 75 rocks the crank 80 and the shaft 61 in a clockwise direction.

60 A tappet 81 (Figs. 1, 3 and 4) fast on the shaft 61, is thereby rocked to contact a stud 82 mounted on the bail arm 60.

As is customary in machines of the type to which this invention is applied, the total 65 taking operation includes two cycles of rota-

tion of the main drive shaft 42 of the machine, during the latter part of the first of which cycles the shaft 61 is rotated slightly farther in a clockwise direction by means to be hereinafter described, which presses the tappet 81 against the stud 82 to rock the bail arm 60 clockwise sufficiently to return the free end of the bail arm into the path of the stud 63 on the differentially movable arm 49 while the latter is at a point some distance above the bail arm 60, so that as the differential arm 49 is restored, its stud 63 strikes the free end of the bail arm 60 and withdraws the locking bail 64 from the notch 65 in the link 41 to permit the release of the depressed "multiple item" key 30.

Mechanism will now be described for giving the shaft 61 its second movement, mentioned above.

A lever 90 (Fig. 6) is pivoted at 91 and is connected at its upper end by a link 92 to an arm 93, pinned to the shaft 61. At its lower end the lever 90 is connected to a pitman 94 guided by a stud 95 mounted in the right hand frame of the machine. The pitman 94 carries a roller 96, adapted to co-operate with a groove in a cam 97, free on the stud 95. The roller 96 is normally in a position withdrawn from the groove and in a notch formed therein. It will be recalled that when the total lever 70 is moved to prepare the machine for a total taking operation the shaft 61 is rocked slightly clockwise. This movement through the mechanism just described will disengage the roller 96 from the notch and move it into cooperative relation with the groove 97. At the same time a slide 98 is moved under the influence of the pitman 94 in a well known manner, to lock the cam 97 to a gear 99, free on the stud 95, so that the cam will be rotated with the gear upon operation of the machine in a manner hereinafter to be described. The gear 99 and the cam 97 receive one counter-clockwise rotation on each total taking operation of the machine. Near the end of the first cycle of operation of the shaft 42, the pitman 94 will be moved to the left by the cam 97 and will rock the shaft 61 clockwise to move the bail 64 out of the notch 65, as described above.

Machine operating and releasing mechanism

The machine is operated manually by means of a crank 100 (Fig. 6) or by an electric motor (not shown). The crank 100 has secured thereto a gear 101 which meshes with gear 99. Pinned to the drive shaft 42 is a gear 102 also meshing with the gear 99. Two clockwise rotations of the crank 100 and gear 101 impart one-half of one counter-clockwise rotation to the gear 99 which in turn gives the gear 102 and the shaft 42 one clockwise rotation on each adding operation of the machine.

The electric motor is not shown or de-

scribed herein as it is old and well known in the art and has no part in the present invention.

The machine is released for operation by pressing a clerk's key (not shown), the transaction key 30 or 31 (Fig. 1) and a starting bar 105 (Fig. 6). This permits a release shaft 106 to be rocked clockwise to release the machine for operation in a manner fully 10 shown and described in the above cited applications. The shaft 106 normally tends to rock clockwise under the influence of a spring 107 compressed between the bottom of a slot 108 in a link 109 and the shoulders of two 15 identical spring pilot arms 110 mounted on an arm 111 pinned to the shaft 106. The shaft 106 is retained in its normal position by a flattened pin 112, on an arm 113 pinned to the shaft 106, contacting with one arm of 20 a bell crank 114, pivoted at 115. Depressing the starting bar 105 will, through the pin 116, carried on a slidable bar 117, engaging the bifurcated portion of an arm 118 which in turn is connected by means of a link 119 25 to a downwardly extending arm of the bell crank 114, rock the bell crank clockwise to remove it from the pin 112, whereupon the spring 107 will rock the shaft 106 clockwise and release the machine for operation.

30 An interlock between the starting bar and transaction key is provided whereby it is necessary to press a transaction key 30 or 31 before the machine can be released by pressing the starting bar 105. Pinned to the shaft 106 is an arm 120 (Fig. 2) which carries a flattened stud 121 normally contacting a projection on an arm 122, pivoted on the shaft 123. The arm 122 is held in contact with a yoke 124 by means of a spring 125. The yoke 124 has an upwardly extending arm 126 contacting a pin 127 carried by the link 40, upon which is swung the upper end of the releasing bar 39. Referring to Fig. 2 it is clear that, when, upon depression of a transaction key 30 or 31, the releasing bar 39 moves to the left, the yoke 124 and the arm 122 will be rocked counter-clockwise to remove the projection thereon from the path of the stud 121, thus leaving the shaft 106 free to be released upon depression of the starting bar 105.

The shaft 106 is restored to its normal position by means of an arm 131 (Fig. 6) pivoted at 91. This arm carries a roller 132 55 adapted to co-operate with a cam groove 133 cut in the side of the gear 99 to give the arm 131 a regular excursion down and then back to its normal position. The arm 131 carries a pin 134 normally engaging a notch in an 60 opening 137 in the link 109. Near the end of an adding operation and near the end of a total taking operation, as the arm 131 is given its excursion, it moves the link 109 down and rocks the shaft 106 counter-clockwise to 65 permit the arm of the bell crank 114 to resume

its normal position in the path of the pin 112. This movement of the shaft 106 also releases the depressed amount keys.

To prevent the shaft 106 from being rocked near the end of the first cycle of a total taking operation, a slot 135 (Fig. 6) is formed in the lower end of the link 109 to co-operate with a stud 136 carried near the right hand end of the pitman 94. When the pitman 94 is moved to the left by the cam 97, as described above, the link 109 is swung to the left, which positions the lower end of the opening 137 therein in the path of the pin 134, so that on its downward movement the pin is ineffective to rock the shaft 106. These parts are restored to their co-operative relationship just before the arm 131 receives its second downward movement in total taking operations. This second movement of the arm 131 will on total taking operations rock 85 the shaft 106 to release the depressed transaction key and restore the parts associated with the starting key and transaction keys to their normal positions.

The machine is provided with a plurality 90 of totalizers mounted on three frames, 140, 141 and 142 (Fig. 1). The totalizer frames 140 and 141 are slid laterally in the machine, on shafts 143, to select the transaction and classification totalizers mounted thereon. 95 The upper totalizer frame 142 carries a grand totalizer which is not under control of the transaction keys.

To select the transaction totalizer, the following mechanism is provided:

Associated with the transaction differential mechanism is a beam 144 (Fig. 1) pivoted on the arm 49 and bifurcated to co-operate with a pin in a link 145. A roller 139 is mounted on the Y-shaped lever 45 for 105 the purpose of bringing the upper convex section of the beam 144 into a constant position against a hub on the differential arm 49. The link 145 is connected at its lower end to an arm 146 secured to one end of a tube surrounding the shaft 147. Secured to the arm 146 is a segment gear 148 meshing with a rack 149, secured to a bar 150 slidably mounted on studs 151. The bar 150 has bent-over flanges 152 in which are shaped cam slots co-operating with rollers (not shown) carried by slides 153. These slides co-operate with projections on the totalizer frames 140 and 141, to slide them laterally in the machine, and select the totalizers to be used, all of 110 which is shown and described in the above mentioned parent application.

While the forms of mechanisms herein shown and described are admirably adapted to fulfill the objects primarily stated, it is 125 to be understood that it is not intended to confine the invention to the forms or embodiment herein disclosed, for it is susceptible of embodiment in various forms all coming within the scope of the claims which follow. 130

What is claimed is:

1. The combination of a bank of keys, a locking detent, locking means for said detent, a releasing bar, and cooperating means on 5 the releasing bar and keys for moving the bar different distances to control the effectiveness of said locking means.
2. The combination of a bank of keys, a locking detent, a releasing bar, and locking 10 means for the locking detent controlled by movement of the releasing bar, and cooperating means on the bar and keys to control the extent of movement of the releasing bar.
3. The combination of a bank of keys, a 15 locking detent, a lock therefor normally urged into locking position, and a release bar adapted to be moved different distances by the various keys for permitting or preventing movement of said lock into locking position.
4. The combination of a bank of keys, a locking detent, a pivoted arm for locking said detent, a bail connected to said arm, a segmental pivoted link provided with a notch in 25 its periphery to receive said bail to permit the locking arm to move into locking position, and means for controlling the position of said segmental link.
5. The combination of a bank of keys, a locking detent, a spring actuated pivoted arm for locking said detent, a bail connected to said arm, a segmental pivoted link provided with a notch in its periphery to receive said bail to permit the locking arm to move 30 into locking position, and means for controlling the position of said segmental link.
6. The combination of a bank of keys, a locking detent, a pivoted arm for locking said detent, a bail connected to said arm, a segmental pivoted link provided with a notch in 40 its periphery to receive said bail to permit the locking arm to move into locking position, and a bar actuated by said keys different distances for moving said segmental link 45 different extents.
7. The combination of a bank of keys, a locking detent, a pivoted arm for supporting said detent, and a pivoted link movable into the path of said arm for preventing release 50 of said keys, and means differentially movable under control of said keys for controlling the movement of said link.
8. The combination of a bank of keys, a locking detent, a pivoted arm for supporting said detent, and a pivoted link movable into the path of said arm for preventing release 55 of said keys, and a bar adapted to be moved differentially by said keys for controlling the movement of said link.
9. The combination of a bank of keys, a locking detent, a releasing bar, coaxially pivoted members actuated by said detent and bar, a pivoted arm movable in the path of 60 the pivoted member supporting the locking
- detent to lock the keys, and high and low portions on said other pivoted member for controlling the pivoted arm.
10. The combination of a bank of keys, a locking detent, a releasing bar, coaxially pivoted members actuated by said detent and bar, a pivoted arm movable in the path of the pivoted member actuated by the locking detent to lock the keys, high and low portions on said other pivoted member for controlling 70 the pivoted arm, and cooperating means on said keys and releasing bar for controlling the position of said high and low portions.
11. The combination of a bank of keys; a differentially movable actuator; a locking 75 detent for the keys; a lock for said detent; a device operable by any of the keys to render the lock ineffective when certain keys are operated; and means on the actuator for moving the lock into ineffective position as the 80 actuator moves into home position when certain other keys are depressed.
12. The combination of a bank of keys; a differentially movable actuator controlled 85 thereby; a locking detent for the keys; an arm for locking said detent to lock the keys; a device adapted to be differentially adjusted by the keys to maintain the arm ineffective 90 when certain of the keys are operated; and a pin on the actuator cooperable with the arm 95 to move the same into an ineffective position as the actuator returns to its home position when certain other keys are depressed.
13. The combination of a bank of keys, a differentially movable actuator controlled 100 thereby, a locking detent for the keys, a spring-actuated arm to retain said detent in position to lock the keys, a differentially adjustable device operable directly by any of the keys and adapted when controlled by 105 certain of the keys to prevent the spring operated arm from becoming effective, and a pin on said actuator co-operable with said arm to move the same into ineffective position as the actuator returns to home position when 110 certain other keys control the differentially adjustable device.
14. The combination of a bank of keys, a differentially movable actuator controlled 115 thereby, a locking detent for the keys, an arm for locking said detent, and movable toward locking position as the actuator moves from home position, means under control of the keys for determining the extent of movement of said arm and its consequent effectiveness, 120 and means on said actuator for returning said arm to home position at the end of an operation thereby permitting the release of a depressed key.
15. The combination of a bank of keys, a 125 differentially movable actuator controlled thereby, a locking detent for said keys, a lock for said locking detent, means on said actuator for preventing the lock from functioning prior to movement of said actuator, 130

and means differentially adjustable under control of the keys for determining the effectiveness of the lock.

16. The combination of a bank of keys, a differentially movable actuator controlled thereby and having advancing and retracting movements, a locking detent for said keys, a spring-actuated lock for said locking detent, means on said actuator for restraining the lock from functioning prior to movement of said actuator, and means whereby the actuator may complete its retracting movement without disturbing the function of the lock.

17. The combination of a bank of keys, a differentially movable actuator controlled thereby, a manually releasable retaining means for said keys, a lock for said retaining means, and means on said actuator cooperable with said lock to move the same to ineffective home position near the end of an operation under control of certain of said keys.

18. The combination of a bank of keys, a differentially movable actuator controlled thereby, a manually releasable retaining means for said keys, a lock for said retaining means, and means on said actuator cooperable with said lock to move the same to ineffective home position near the end of an operation under control of certain of said keys, said cooperable means being ineffective under control of the remaining keys.

19. The combination of a bank of keys, a differentially movable actuator controlled thereby, a manually releasable retaining means for said keys, a lock for said retaining means, means on said actuator cooperable with said lock to move the same to ineffective home position near the end of an operation under control of certain of said keys, said cooperable means being ineffective under control of the remaining keys, and a total control means for causing said cooperable means to be effective under control of said remaining keys.

45. In testimony whereof I affix my signature.
